UNITED STATES PATENT OFFICE.

ALKOURY ANTONIOUS ABIZAID, OF WASHINGTON, DISTRICT OF COLUMBIA.

BUCKLE.

1,337,181.

Specification of Letters Patent.

Patented Apr. 20, 1920.

Application filed August 31, 1916. Serial No. 117,848.

To all whom it may concern:

Be it known that I, ALKOURY ANTONIOUS ABIZAID, a subject of the Sultan of Turkey, residing at Washington, District of Columbia, have invented certain new and useful Improvements in Buckles, of which the following is a specification.

This invention relates to certain novel and useful improvements in buckles and has 10 particular application to a suspender buckle.

In carrying out the present invention, it is my purpose to provide a buckle which will be constructed in such manner that the same may be readily and quickly applied to the suspender and adjusted thereon and which, when in adjusted position, may be securely and effectively locked against accidental movement along the strap or webbing of the suspender.

20 It is also my purpose to provide a buckle for suspenders and the like which may be manufactured and marketed at small cost and which will embody comparatively few parts and these so arranged and correlated 25 as to reduce the possibility of derangement to a minimum.

With the above and other objects in view, the invention consists in the construction, combination and arrangement of parts here- 30 after set forth in and falling within the scope of the claims.

In the accompanying drawing;

Figure 1 is a perspective view of a buckle constructed in accordance with my present 35 invention,

Fig. 2 is a similar view showing a modified form of the buckle,

Fig. 3 is a perspective view of another modified form.

40 In the preferred form of my invention, shown in Fig. 1, the buckle comprises a single sheet of metal stamped to form a substantially rectangular frame 1 and tongues 2 integral with the respective end bars of the frame 1 and projecting toward each other. These tongues 2 are offset outwardly from the frame 1 and the inner ends thereof are spaced apart a distance sufficient to permit the strap or webbing of the suspender to be 45 slipped into the space between the tongues and frame. Integral with the lower bar of the frame 1 is a lug 3 arranged between the inner ends of the tongues 2 and projecting slightly toward the tongues to bite into the 50 material of the strap. In the present instance the upper edges of the tongues 2 are

formed with teeth designed to bite into the strap.

In practice, one end portion of the suspender strap or webbing is slipped into the 60 space between the tongues and the frame through the space between the inner ends of the tongues and the strap is then carried over the toothed edges of the tongues and passed through the loop of the suspender 65 and then carried up through the space between the tongues and the top bar.

7 indicates a clamp member having ears or bearings 8 formed thereon and adapted to surround the top bar of the frame adjacent to the respective end bars of the frame. The clamp member 7 is preferably formed of sheet metal of which the ears 8 are integral parts and formed on the edge of the clamp member 7 between the ears 8 are teeth 75 9 arranged at an angle to the main body portion of the clamp member and designed to bite into the webbing after the latter has been drawn up through the space between the top bar and that portion of the webbing 80 turned down over the tongues 2 so as to hold the buckle in adjusted position upon the strap or webbing.

If desired, the tongues 2 may be dispensed with and the bar 5 stamped from the frame 85 and arranged in the same manner as the tongues and the upper edge of the bar is preferably formed with teeth 6, shown in Fig. 2. In this case the lug 3 on the lower bar is pressed inwardly toward the bar 5 in 90 order to coöperate with the bar 5 to clamp the webbing to the buckle. In the initial threading of the strap through the buckle shown in Fig. 2, the buckle end of the strap is passed into the space between the bar 5 and the frame and the strap threaded in the manner hereinbefore described with reference to Fig. 1.

The buckle shown in Fig. 4 is similar to the buckle shown in Fig. 3, except that the 100 bottom bar is dispensed with and the cross bar is provided with a depending lug 13 arranged in a position between the inner ends of the tongues and this lug is provided with outwardly projecting prongs 46 that are 105 adapted to bite into the webbing.

If desired, the inner or web engaging sides of the different bars and tongues may be roughened in order to insure a good gripping action between the bars and the 110 webbing, while the lower edges of the bottom bars may be equipped with outwardly

projecting knife edged grippers. Again, the tongues and the bottom bars of the buckles shown in Figs. 1 and 3 may be corrugated so as to provide good gripping surfaces. The lowermost slot in each buckle frame is preferably of less length than the top slot so that the end portion of the webbing that is passed through the bottom slot will be snugly held therein.

13 I claim:

1. A buckle comprising a frame, means on said frame offset outwardly therefrom and coöoperating with said frame to clamp the fabric, and a lug on said frame in juxtaposition to said first named means and co-operating therewith to securely hold the fabric to said frame.

2. A buckle comprising a frame, means on said frame offset outwardly therefrom and formed with teeth adapted to bite into the material of the fabric and coöoperating with said frame to clamp the fabric, and a lug

on said frame coöperating with said means to securely hold the fabric to the frame, said lug being arranged centrally of said means 25 and of said frame.

3. A buckle comprising a frame, means on said frame offset outwardly therefrom and formed with teeth adapted to bite into the material of the fabric and coöoperating 30 with said frame to clamp the fabric, and a lug on said frame coöperating with said means to securely hold the fabric to the frame, said lug being arranged centrally of said means and of said frame, said lug having a roughened surface confronting said means.

In testimony whereof I have hereunto set my hand in presence of two subscribing witnesses.

ALKOURY ANTONIOUS ABIZAID.
